DISPENSER FOR WRAPPING MATERIAL

Bernard Robinson, 708 Tomahawk,
Prairie Village, Kans. 66208

Filed Dec. 13, 1965, Ser. No. 153

Term of patent 3½ years

(Cl. D52—2)

FIG. 1 is a top plan view of the dispenser for wrapping material, showing my new design;

FIG. 2 is a front elevational view thereof;

FIG. 3 is an elevational view of one end thereof;

FIG. 4 is a rear elevational view; and

FIG. 5 is a perspective view of the dispenser for wrapping material.

I claim:

The ornamental design for a dispenser for wrapping material, as shown.
